UNITED STATES PATENT OFFICE.

HOWARD D. COLMAN, OF ROCKFORD, ILLINOIS, ASSIGNOR, BY MESNE ASSIGNMENTS, TO BARBER-COLMAN COMPANY, OF ROCKFORD, ILLINOIS, A CORPORATION OF ILLINOIS (1922).

TEXTILE APPARATUS.

Application filed June 7, 1920, Serial No. 386,948. Renewed September 19, 1927.

In application Serial No. 237,191, filed May 29, 1918, by Howard D. Colman and Burt A. Peterson (now Patent No. 1,614,718, dated January 18, 1927), there is disclosed a spinning machine adapted to spin enough coils of yarn on the upper end of the bobbin to form a small mass above the main yarn mass. These coils of yarn are connected by a strand of yarn to the main 10 yarn mass, and when stripped off the bobbin they are followed by said strand, thus affording means for readily obtaining the free end of the yarn on the bobbin.

The present invention relates to means 15 for stripping from the bobbin the coils of yarn above referred to.

A particular object of the invention is to provide such stripping means in conjunction with means for taking a bobbin from 20 a magazine and inserting it in the shuttle of a loom.

In the accompanying drawings, Fig. 1 is a fragmental side elevation of a loom embodying the features of my invention. Fig. 25 2 is a fragmental view looking from the left hand side of Fig. 1. Fig. 3 is a sectional view taken approximately in the plane of line 3—3 of Fig. 1. Fig. 4 is a view of the weft-replenishing mechanism. Fig. 30 5 is a view similar to that of Fig. 4, but showing the parts in a different position. Fig. 6 is a sectional view taken approximately in the plane of line 6—6 of Fig. 1. Fig. 7 is a top plan view of certain parts of 35 the mechanism. Fig. 7^a is a perspective view of one of the parts shown in Fig. 7. Fig. 8 is a top plan view of the weft-replenishing mechanism. Fig. 9 is a sectional view taken approximately in the plane of dotted line 9—9 of Fig. 2. Fig. 10 is a view taken 40 approximately in the plane of dotted line 10—10 of Fig. 4. Fig. 11 is a view taken in the plane of line 11—11 of Fig. 4. Fig. 12 is a detail view of one of the butt-clamping 45 jaws. Fig. 13 is a detail view of a bracket comprised in the machine. Fig. 14 is a view taken in the plane of dotted line 14—14 of Fig. 4. Fig. 15 is a view similar to Fig. 14 but showing the parts in a different position. Fig. 16 is a section on line 50 16—16 of Fig. 14.

The invention is herein shown as embodied in a loom of well known construction, 1 being one of the lay swords, 2 the lay, 3 (Fig. 9) the race plate, and 4 the

shuttle box at the weft-replenishing side of the loom. 5 is a shuttle of well known construction.

In describing the embodiment of the invention which is shown in the drawings, reference will be made to "bobbins", since they are the particular kind of weft carrier which is illustrated, but it should be understood that the invention may be embodied in apparatus intended for handling other forms of weft carriers.

The bobbin 6 herein shown has a butt 7 which is equipped with a plurality of rings 8 to enable it to be grasped and held by the usual bobbin-holding jaws (not shown) in 70 the shuttle. The tip 9 of the bobbin is provided with a suitable number of longitudinal grooves 10 terminating upon the rounded end of the tip. (See Fig. 14.) Preferably the grooves 10 are formed in the periphery of a metallic sleeve fitting upon the wooden tip of the bobbin. The periphery of the sleeve is tapered slightly toward its outer end for a purpose to appear herein-after. The bobbin carries a supply yarn 75 mass *a* and a small mass of yarn *b*, the yarn *b* being wound upon the grooved portion of the tip 9 at a substantial distance from the yarn mass *a*. The grooves 10 extend beneath the mass *b*. Said mass *b* is connected 80 to the yarn mass *a* by means of a strand *c*. *d* is the free end of the yarn.

The reserve supply of bobbins is contained within a magazine which may be of any suitable character. Herein is shown a magazine 90 11 rigidly secured to the supporting framework and adapted to contain a single column or stack of bobbins, the bobbins resting upon one another. The butt of the lowermost bobbin is supported by the ledge 12 (Figs. 9 and 10) of a gate 13, said gate normally underlying the magazine 11 and being rigid with an arm 14 which is mounted to swing upon the axis 15 in the supporting frame work. The arm 14 and the parts carried thereby constitute means for normally closing the lower end of the magazine and for transporting bobbins singly and successively into position to be placed in the shuttle. Rigid with the arm 14 is an arm 16 to which 95 is pivoted a rod 17 that extends slidably through a stud 18 pivoted to a lever 19. The lever 19 is pivoted to the loom framework at 20 and has a roller stud 21 that bears 100 against a cam 22 on a shaft 23. A contrac- 105 110

tile spring 24 connected to the lever 19 and anchored to the framework serves to hold the roller stud 21 in contact with the cam 22. An expansion spring 25 surrounding the 5 lower portion of the rod 17 is interposed between a nut 26 on the lower end of the rod 17 and the stud 18 and serves to keep said stud pressed against a collar 27 on the rod 17. The gate 13 is thus yieldingly 10 swung in both directions when weft replenishment is necessary, the arm 14 being locked against movement at other times, and the springs 24 and 25 yielding as the shaft 23 continues revolving.

15 The tip of the lowermost bobbin is supported upon a finger 28 (Fig. 4) which is pivoted at 29 to the magazine. The finger 28 is normally held in position to support the tip of the lowermost bobbin by means of 20 a contractile spring 30, said spring holding the finger against a stop 31. When the finger 28 is withdrawn, the tip of the bobbin descends upon a shelf 32 (Figs. 4, 6 and 7) fixed to the magazine 11 and underlying 25 the end of the finger 28. At one side of the shelf 32 is a wall 33 to prevent the displacement of the bobbin tip in that direction.

The means for swinging the finger 28 aside to allow the bobbin tip to drop upon 30 the shelf 32 comprises a shoulder 34 (Fig. 4) on the gate 13 which is arranged to engage a pin 35 on said finger when the gate is swung into the position shown in Fig. 5. The bobbin tip is prevented from 35 slipping off the shelf 32 by means of a guard plate 36 on the gate 13. The guard plate is shown in Figs. 6 and 8. By the time the finger 28 has moved out from under the bobbin tip, the ledge 12 has moved out from 40 under the butt of the bobbin, whereupon the bobbin butt drops upon a ledge 37 (Figs. 9 and 10) formed on a bracket 38 fixed in the machine frame.

Means is provided to clamp the bobbin so 45 that it shall be supported in proper position after the butt of the bobbin has been carried off the ledge 37 and has been moved off the shelf 32. The said means comprises a jaw 39 (Figs. 6 and 9) fixed to the gate 13 in 50 prolongation of the ledge 12, the face of said jaw being made concave and grooved to fit the bobbin butt and its rings 8. 40 (Figs. 9, 10 and 12) is a jaw fixed to a shaft 41 carried by the arm 14. The free end of the 55 jaw 40 is socketed and grooved to correspond with the shape of the bobbin butt. To the shaft 41 is fixed an arm 42 to which is connected a contractile spring 43 which serves to move the jaw 40 to clamp the bobbin butt 60 between the jaws 39 and 40. When there is no bobbin between the jaws 39 and 40, the action of the spring 43 is limited through contact of the jaw 40 with the portion 44 (Fig. 10) of the gate 13. As the gate 13 65 swings in the direction to carry the ledge 12

out from under the lowermost bobbin in the magazine, a pin 45 (Fig. 9) on the jaw 40 stops against the ledge 37, as indicated in dotted lines in Fig. 9, thereby causing the jaws of the clamp to be separated to receive the bobbin butt. As the gate 13 swings back to its normal position, the clamp jaws close upon the bobbin butt and grip the bobbin so as to support it firmly. The clamp 70 39—40 constitutes the sole support of the 75 bobbin while the latter is being carried away from the magazine.

Means is provided for stripping the yarn mass *b* off the tip of the bobbin while the bobbin is being carried from the shelf 32 and the ledge 37 to the position where it is to await transfer to the shuttle. This means comprises a stripping element which may be of any suitable construction. As herein shown, said element comprises an 80 annular series of spring hooks 46 (Fig. 14). The shanks of said hooks lie within radial slots in a sleeve 47 with the points of said hooks extending toward the axis of the sleeve. The sleeve 47 is slidably mounted in a bearing 48 in the gate 13, the sleeve being in axial alinement with a bobbin held by the jaws 39 and 40. The reduced outer end of the sleeve 47 and the shanks of the 85 spring hooks 46 are clamped in an arm 49 (Fig. 8) which is fixed to one end of a rod 50 that is slidably mounted in a bearing 51 on the gate 13. The other end of the rod 50 is loosely pivoted to a lever 52 (Figs. 9 and 10) which is pivoted to the gate 13 upon the axis 53. The lever 52 carries a roller stud 54 which is held in contact with a cam flange 55 (Figs. 5 and 13) on the bracket 38 by means of a contractile spring 56 (Fig. 10). Said spring is secured at one end to the gate 13 and at its other end to the rod 50. As the gate 13 swings from the position shown in Fig. 5 to that shown in Fig. 4, the sleeve 47 is slid onto the tip of the bobbin and withdrawn therefrom. When the sleeve 47 is moved toward the bobbin, the spring hooks 46 yield radially outwardly so as to pass onto the bobbin tip and over the 90 yarn mass *b*, the points of most, if not all, of the hooks entering the grooves 10. When the sleeve 47 is moved away from the bobbin the hooks 46 carry the yarn mass *b* along with them, the strand *c* unwinding from the 95 yarn mass *a*. The devices just described may be termed means for extending the end 100 of the thread on the bobbin. The reason for slightly tapering the grooved portion of the bobbin tip is to prevent the yarn mass *b* from being pushed toward the yarn mass *a* by the hooks 46.

When the arm 14 reaches the position shown in Fig. 4, it is locked in such position by means of a latch 57 (Fig. 4) which is pivoted at 58 to the machine framework, said latch having a shoulder 59 which is 105 110 115 120 125 130

adapted to engage a pin 60 on the arm 14. The latch is yieldingly held in engagement with the pin 60 by means of a bowed spring 61 which is connected to the machine frame 5 at 62 and to an arm 63 at 64, the arm 63 being rigid with the latch 57.

The loom may be provided with any suitable means for initiating the automatic transfer of the bobbin from the clamp 39-40 10 to the shuttle when the running weft becomes exhausted through breakage of the thread or unwinding of the yarn on the bobbin in the shuttle. Since such means is well known in the art and may be of various 15 types, it has been deemed unnecessary to illustrate any such mechanism herein. It may be assumed that the loom is provided with the usual starting shaft *s*, which is rocked in order to set in motion the filling 20 or weft-changing mechanism whenever there is a necessity for the replenishment of filling or weft in the shuttle, due either to the exhaustion, breakage or approaching exhaustion of the weft in use. The effect of the 25 movement of this starting shaft is to bring into action a transerrer which transfers a fresh bobbin from the clamp 39-40 into the shuttle 5 on the lay, at the same time ejecting the spent bobbin from the shuttle. Referring now to Fig. 5, 65 is the transerrer, said transerrer consisting of a lever or arm which is pivotally mounted upon the axis 66 and is normally held uplifted as shown in Fig. 5 by a torsion spring 67 (Fig. 8). The 30 transerrer further comprises a rod 68 (Fig. 8) fixed to the lever 65 and carrying a fork 69. The end 70 of the lever 65 is adapted to engage the butt of the bobbin, while the fork 69 is located in position to engage the tip of the bobbin. Preferably the fork 69 is lined with suitable yielding material in order that the bobbin tip shall not be marred and to prevent an occasional breakage of the 35 extended thread-end. 65^a is a stop determining the normal position of the transerrer, said stop being fixed to the machine frame in position to be engaged by a pin 71 on the transerrer (see Figs. 5 and 8). When the transerrer descends, the bobbin is transferred from the position indicated at *x* in 40 Fig. 9 to the shuttle 5, the spent bobbin being forced from the shuttle by the incoming bobbin. In passing from the clamp 39-40 to the bobbin-holding jaws in the 45 shuttle the butt of the bobbin is guided by a stationary member 72 (Figs. 9 and 11), the face of said guide member being grooved for the passage of the rings 8 on the bobbin butt. The bobbin butt is further guided and 50 restrained by a finger 73 (Figs. 9 and 10) which is pivoted to the gate 13 at 74 and is normally held in contact with the lower side of the clamp jaw 39 by a torsion spring 75. The end of the finger 73 partially underlies 55 the bobbin butt when the bobbin is held in

the clamp 39-40 and it swings downwardly as the bobbin is forced out of the clamp.

As the bobbin is transferred to the shuttle, the tip of the bobbin is guided and restrained by means of a finger 76 (Figs. 5 70 and 8) which is pivoted to a stationary support 77 at 78. A torsion spring 79 normally holds the finger 76 in the position shown in Fig. 5, the action of the spring being limited 75 through contact of a stop 80 on the finger 76 with a stop 81 on the support 77.

The means for disengaging the latch 57 from the pin 60 comprises an arm 82 rigid with said latch and extending in position to be engaged and moved by the pin 71 when the transerrer 65 pushes the new bobbin into the shuttle. The pin 71 causes the arm 63 to swing into contact with a stop pin 83 where it is held by the action of the bowed 80 spring 61.

The means for restoring the latch to a position where it can engage the pin 60 upon the return movement of the arm 14 comprises a link 84 (Figs. 4 and 11) having an elongated opening 85 into which extends a pin 86 on the arm 14. The link 84 also has an elongated opening 87 to receive a pin 88 set in the arm 63. A contractile spring 89 stretched between the pin 88 and a lug on the link 84 yieldably connects the arm 63 to the arm 14.

Assuming the parts to be in the position shown in Fig. 4 the operation is as follows: When a fresh bobbin is to be substituted for the one in the shuttle, the transerrer 65 is given a rapid oscillation, whereby the bobbin held by the clamp 39-40 is driven out of said clamp and into the shuttle. The strand *c* is later parted in the usual or any suitable manner. The engagement of the pin 71 with the arm 82 causes the latch 57 to move into the position shown in Fig. 9. In the rotation of the cam 22, the arm 14 is moved into the position shown in Fig. 5 and then back to the normal position illustrated in Fig. 4. As the arm 14 moves into the position represented in Fig. 5, the ledge 12 moves out from under the butt of the lowermost bobbin in the magazine, whereupon the butt of the bobbin drops onto the ledge 37 (Figs. 9 and 10) and lies between the clamping jaws 39 and 40. At the same time, the finger 28 moves out from beneath the tip of the bobbin, which thereupon drops upon the shelf 32 and lies between said finger and the guard plate 36. The arm 14 then swings back to normal position, the bobbin being supported in horizontal position by the clamp 39-40. In the return movement of the arm 14, the sleeve 47 is slipped over the tip of the bobbin and withdrawn, carrying with it the coil of yarn *b* and unwinding the strand *c* from the yarn mass *a*.

As the arm 14 swung into the position represented in Fig. 5, the link 84 and spring 120

89 caused the latch 57 to swing down into the position shown in said figure. In the return movement of the arm 14, the pin 60 slides under the latch and moves into engagement with the shoulder 59 as the bobbin reaches the position for transfer to the shuttle. Here the bobbin stands with the strand *c* held by the hooks 46 until occasion arises for weft replenishment.

10 The waste yarn which collects on the hooks 46 may be removed at convenient intervals.

The reason for yieldingly connecting the arms 14 and 63 is to allow the arm 14 to make its full movement even though the 15 arm 63 should be accidentally held against movement.

While the present embodiment of the invention has been described with considerable particularity, it will be understood that the 20 invention is not limited to the mechanisms and arrangements of parts herein shown, but that, on the contrary, many changes may be made without departing from the scope of the invention as defined by the appended 25 claims.

I claim as my invention—

1. The combination with means for supporting a bobbin having a longitudinal groove in its tip, the end of the thread on 30 the bobbin being coiled on the tip, of a hook arranged to be reciprocated longitudinally of the tip to enter said groove and withdraw said coil from the tip.

2. The combination with means for supporting a bobbin, the end of the thread on 35 the bobbin being coiled on the tip, of a circular series of hooks arranged to be reciprocated longitudinally of the tip to withdraw said coil from the tip.

40 3. The combination of a bobbin magazine, a transerrer, a reciprocatory device to move bobbins one at a time from the magazine to the transerrer, the end of the thread on the bobbin being coiled on the tip, and a hook 45 carried by said device and arranged to be reciprocated longitudinally of the tip to withdraw said coil from the tip during the travel of the bobbin from the magazine to the transerrer.

50 4. The combination of a bobbin magazine, withdrawable means to support the lowermost bobbin in the magazine, a clamp to receive the butt of said bobbin when said supporting means is withdrawn from beneath 55 the bobbin, and means for moving said clamp to carry the bobbin away from the magazine, said clamp being adapted and arranged to constitute the sole support of the bobbin while the latter is being carried away 60 from the magazine.

5. The combination of a bobbin magazine, a movable structure having means to support the lowermost bobbin in the magazine, a clamp on said structure to receive the butt 65 of said bobbin when said structure is moved

to carry said supporting means out from beneath the bobbin, means for driving the bobbin out of the clamp, and means for moving said structure to carry the bobbin to said driving means, said clamp being 70 adapted and arranged to constitute the sole support of the bobbin while the latter is being carried to said driving means.

6. The combination of a bobbin magazine, a movable structure having means to support the lowermost bobbin in the magazine, and a clamp on said structure to receive the butt of 75 said bobbin when said structure is moved to carry said supporting means out from beneath the bobbin, said clamp being 80 adapted firmly to grip the butt of the bobbin.

7. The combination of a bobbin magazine, a pivoted structure having means to support the lowermost bobbin in the magazine, a clamp on said structure to receive the butt of 85 said bobbin when said structure is swung to carry said supporting means out from beneath the bobbin, means for disengaging the bobbin from the clamp, and means for swinging said structure to carry a bobbin to said disengaging means, said clamp being adapted and arranged to constitute the sole support of the bobbin while the latter is being carried to said disengaging means.

8. The combination of a bobbin magazine, a pivoted structure having means to support the lowermost bobbin in the magazine, a clamp on said structure to receive the butt of 90 said bobbin when said structure is swung to carry said supporting means out from beneath the bobbin, means for inserting a bobbin into a shuttle, and means for swinging said structure to carry the bobbin from the magazine to said inserting means, said clamp being adapted and arranged to constitute the sole support of the bobbin while the latter is being carried to said inserting means.

9. The combination of a bobbin magazine, a transerrer, a device to move a bobbin 110 from the magazine to the transerrer, and means to lock said device in operative relation to the transerrer, the transerrer being arranged to operate said locking means to release said device.

10. The combination of a bobbin magazine, a structure movable to and fro, a clamp on said structure to receive the butt of a bobbin at the magazine, means for extending the end of the thread on said bobbin while the latter is held by the butt thereof, means for driving the bobbin out of the clamp, and means for moving said structure to carry the bobbin to said driving means.

11. The combination of a bobbin magazine, a movable structure having means to support the lowermost bobbin in the magazine, a clamp on said structure to firmly grip the butt of said bobbin when said structure is moved to carry said supporting 120 130

means out from beneath the bobbin, means for extending the end of the thread on the clamped bobbin, means for driving the bobbin out of the clamp, and means for moving 5 said structure to carry the bobbin to said driving means.

12. The combination of a bobbin magazine, a movable structure having means to support the lowermost bobbin in the magazine, a clamp on said structure to firmly grip the butt of said bobbin when said structure is moved to carry said supporting means out from beneath the bobbin, means located on said movable structure for extending the end of the thread on the clamped bobbin, means for driving the bobbin out of the clamp, and means for moving said structure to carry the bobbin to said driving means.

13. The combination of a bobbin magazine, a pivoted structure arranged to receive a bobbin from the magazine, a clamp on said structure to hold the butt of said bobbin, and a hook reciprocable in substantial alignment with a bobbin held by said clamp to engage a coil of yarn on the tip of the bobbin and withdraw said coil.

14. A loom having, in combination, a magazine, a transerrer, a clamp arranged 30 to firmly grip the butt of a bobbin at the magazine and carry the bobbin into operative relation to the transerrer, and a device to engage the tip of the bobbin to withdraw the weft-end therefrom and hold it extended 35 pending transfer of the bobbin.

15. A loom having, in combination, a magazine, a transerrer, a clamp arranged to firmly grip the butt of a bobbin at the magazine and carry the bobbin into operative relation to the transerrer, and a device to engage the tip of the bobbin to withdraw the weft-end therefrom.

16. In a loom the combination of a bobbin magazine, a shuttle disposed in laterally spaced relation with respect thereto, a rocker arm operating between said magazine and shuttle, a clamp mounted on said arm arranged to receive the butt end of a bobbin when said arm is swung to said magazine, a 45 weft end extender mounted on said arm and disposed alongside the tip of the bobbin held in said clamp, means for operating said extender during the swing of said arm from said magazine to said shuttle, and means operable at the shuttle to eject said bobbin from said clamp into said shuttle.

17. In a loom, the combination of a bobbin magazine, a shuttle disposed in laterally spaced relation with respect thereto, a rocker 60 arm operating between said magazine and shuttle, a clamp mounted on said arm arranged to receive the butt end of a bobbin when said arm is swung to said magazine, a weft end extender mounted on said arm for reciprocation longitudinally relative to

the bobbin toward and away from said clamp, said extender being normally alongside of and out of engagement with the tip end of the bobbin held in said clamp, means automatically operable in the swinging 70 movement of said arm from said magazine to said shuttle for reciprocating said extender over the tip end of said bobbin and off again to extend the weft end, and ejecting means to force the bobbin from said clamp into said shuttle.

18. In a loom, the combination of a bobbin magazine, a shuttle disposed in laterally displaced relation with respect thereto, a rocker arm arranged to swing between said magazine and said shuttle to move bobbins from the former to the latter and having means for holding the bobbin at the butt end thereof leaving the tip end free, automatically operable means arranged in the swing of said arm from the magazine to the shuttle to pass over the tip end of the bobbin and off again to extend the weft end, and means arranged to cause the release of 85 said bobbin to said shuttle.

19. The combination in a loom, of a support to hold a bobbin by the butt end thereof, said bobbin having a tip of tapering form smaller at the outer end thereof, arranged to have the end of the thread on the bobbin wound thereon, and a hook arranged for reciprocation longitudinally of 90 said tip over said coil to withdraw the coil from the tip.

20. The combination in a loom, of a support for holding a bobbin by the butt end thereof, said bobbin having a tip end of tapering form smaller at the outer end and a groove extending longitudinally of said tip, the end of the thread on the bobbin being coiled on the tip over said groove, and a hook arranged to be reciprocated longitudinally of the tip over said coil for entry in said groove behind the coil so that upon withdrawal of said hook the coil is removed 105 from the tip.

21. A loom having, in combination, a bobbin magazine, a gate movable to and fro beneath the magazine, said gate having a ledge which normally underlies and supports the lowermost bobbin in the magazine, a finger pivoted to the magazine to support the tip of the lowermost bobbin, a spring normally holding said finger in tip-supporting position, a part on the gate arranged to withdraw said finger when the gate is moved into bobbin-receiving position, a shelf on the magazine below the finger to receive the tip of the bobbin when the finger is withdrawn, a part at one end of said shelf to prevent displacement of the tip in that direction, a guard on the gate to prevent the tip from slipping off the shelf, a stationary ledge onto which the butt of the bobbin drops when the first mentioned ledge has 110 115 120 125 130

- been moved out from under the butt of the bobbin in the movement of the gate into bobbin-receiving position, a jaw on the gate at one end of the first mentioned ledge, a 5 spring-actuated jaw mounted on the gate opposite the first mentioned jaw, the butt of the bobbin dropping into position between said jaws when the gate is moved into bobbin-receiving position, and means to move 10 the second jaw away from the first jaw as the gate moves into bobbin-receiving position.
22. A loom having, in combination, a bobbin magazine, a gate movable to and fro beneath the magazine, said gate having a ledge which normally underlies and supports the lowermost bobbin in the magazine, a finger pivoted to the magazine to support the tip of the lowermost bobbin, a spring normally 20 holding said finger in tip-supporting position, means to withdraw said finger when the gate is moved into bobbin-receiving position, a shelf on the magazine below the finger to receive the tip of the bobbin when 25 the finger is withdrawn, a stationary ledge onto which the butt of the bobbin drops when the first mentioned ledge has been moved out from under the butt of the bobbin in the movement of the gate into bobbin- 30 receiving position, a jaw on the gate at one end of the first mentioned ledge, a spring-actuated jaw mounted on the gate opposite the first mentioned jaw, the butt of the bobbin dropping into position between said jaws 35 when the gate is moved into bobbin-receiving position, and means to move the second jaw away from the first jaw as the gate moves into bobbin-receiving position.
23. In a loom, in combination, a bobbin magazine, a gate movable to and fro beneath the magazine, said gate having a ledge which normally underlies and supports the lowermost bobbin in the magazine, a finger pivoted to the support to support the tip of the 40 lowermost bobbin, a spring normally holding said finger in tip-supporting position, a part on the gate arranged to withdraw said finger when the gate is moved into bobbin-receiving position, a shelf on the magazine 45 below the finger to receive the tip of the bobbin when the finger is withdrawn, and a stationary ledge onto which the butt of the bobbin drops when the first mentioned ledge has been moved out from under the butt of the bobbin in the movement of the gate into bobbin-receiving position.
24. In a loom, in combination, a bobbin magazine adapted to contain a column of 50 bobbins, a gate movable to and fro beneath the magazine, said gate having a ledge which normally underlies and supports the lowermost bobbin in the magazine, a stationary ledge onto which the butt of the bobbin drops when the first mentioned ledge has been moved out from under the butt of the bobbin in the movement of the gate into bobbin-receiving position, a jaw on the gate at one end of the first mentioned ledge, a spring-actuated jaw mounted on the gate opposite the first mentioned jaw, the butt of 55 the bobbin dropping into position between said jaws when the gate is moved into bobbin-receiving position, and means to move the second jaw away from the first jaw as the gate moves into bobbin-receiving position.
25. A loom having, in combination, a bobbin magazine, a transerrer, a structure movable to and fro between the magazine and the transerrer, a clamp on said structure to grip the butt of a bobbin and to constitute the sole support of the bobbin while the latter is being carried to the transerrer, and a means on said structure for extending the 60 end of the thread on the bobbin.
26. A loom having, in combination, a bobbin magazine, a transerrer, a structure movable to and fro between the magazine and the transerrer, and a clamp on said structure to grip the butt of a bobbin and to constitute the sole support of the bobbin while the latter is being carried to the transerrer.
27. A loom having, in combination, a bobbin magazine, a clamp adapted and arranged to support a bobbin solely by the butt thereof, means for drawing the thread off the tip of the bobbin while so supported, and means for moving the clamp to carry the bobbin away from the magazine and into transfer 65 position.
28. A loom having, in combination, a bobbin magazine, a transerrer, a clamp arranged to grip the butt of a bobbin released from said magazine and adapted to constitute the sole support of the bobbin while the latter is being carried to the transerrer, and means for moving the clamp to and fro between the magazine and the transerrer in accordance with the necessity for weft replenishment, and means for drawing the thread off the tip of the bobbin while held by said clamp.
- In testimony whereof, I have hereunto set my hand.
- HOWARD D. COLMAN.
